FELT AND METHOD OF MAKING

Bela Freyer, Newburgh, N. Y., assignor to American Felt Company, New York, N. Y., a corporation of Massachusetts

Application July 20, 1935, Serial No. 32,451

3 Claims. (Cl. 28—1)

This invention relates to felts and their manufacture. More particularly the invention relates to felts and the process of making them in which a figure or color combination is produced in the felt by the assembling and uniting of different pieces during the formation of the felt.

Prior to my invention numerous efforts have been made to provide surface decoration on felts. Thus felts have been printed, painted, embroidered, embossed, perforated and decorated in various other ways. Unfortunately, however, none of these is entirely satisfactory; especially because the wear to which the decorated surface is subjected tends to remove at least part of the surface decoration before the felt is otherwise worn sufficiently to impair its usefulness.

It is an object of my invention, therefore, to provide, by a novel method, a felt which is decorated by a figure or color contrast which is formed in the structure of the felt itself, and therefore, will remain substantially throughout the useful life of the felt.

In the accompanying drawing I have shown several embodiments of my invention. These have been chosen for purposes of illustration and with a view to explaining my invention so that those skilled in the art may apply it in innumerable forms according to varying requirements and circumstances. It is to be understood, therefore, that the invention is not limited to the particular forms illustrated.

In Fig. 1, I have shown in plan view a waffle pattern made according to my invention.

Fig. 2 is a cross section taken on line 2—2 of Fig. 1.

Fig. 3 is a cross section similar to Fig. 2, but showing a slightly modified form.

Fig. 4 is a view similar to Fig. 1 of an "expanded lath" pattern made according to my invention.

Fig. 5 is a plan view illustrating one way of forming the pattern of Fig. 4.

Figs. 6 and 7 are similar cross section views of a part of a pattern using three different layers of material shown respectively as initially assembled and as finally completed, and,

Fig. 8 is a cross section view similar to Figs. 2, 3, and 7, showing another embodiment of the invention.

Referring first to Fig. 1, the pattern there illustrated is made up of a perforated surface layer 10 and an under layer 11, exposed through the perforations 12 of the layer 10. These layers 10 and 11 are integrally united with each other by felting them together, and, in the cases illus-

trated in Figs. 2 and 3, are similarly united with a third base layer 13.

The pattern may be formed either by color contrast, in which case the layers 10 and 11 are of different colors or of texture contrast, in which case the layers 10 and 11 are preferably of different materials, i. e., of different types of fiber, or the pattern may depend entirely upon differences in level, as in the case of an embossed material, in which case the layers 10 and 11 may be of identical stock. Even in this case, however, a difference in texture ordinarily will appear due to the fact that the trimming of the loose fibers at the surface of the finished felt, will, unless special care is taken to prevent it, be closer on the high areas of the layer 10 than on the lower areas of the layer 11, and thus, the lower figure areas will give the appearance of a soft loose texture while the surface of the layer 10 between the figures will appear harder and denser.

A striking and desirable texture contrast may also be produced by making either the perforated layer 10 or an exposed under layer 11 or 15 (Figs. 6 and 7) of a textile fabric (textile, knitted, etc.). The textile fabric in such case is felted with the adjacent felt layer during the pulling and/or hardening operations and if the fabric layer is perforated this felting operation will so secure the thread end in the perforations as to prevent any fraying of the edges.

If a color contrast is desired the stock of one or both layers may be dyed at any stage before they are joined, or the layers 10 and 11 may be made of stocks which have different dyeing properties, in which case the completed felts may be cross dyed, e. g., by the processes well known in the cross dyeing of textiles. In this way the surface layer 10 may be made to take up one color and the under layer 11 to take up another color, and if desired, the base layer 13 may be of a stock which takes up either of these colors, or by making it of a different type of stock it may be given a third color.

Since the several layers of which the felt is composed are united by felting, obviously these layers will be put through at least the final stages of the felting process after they have been assembled. According to the preferred process embodying my invention, the several layers of felt are first formed and partially hardened by the usual felting processes. At least one of these layers is perforated by punching out the areas which form the figure or pattern. These layers are then assembled as will be obvious from the

figures of the drawing and are united by the final stages of the hardening and fulling operations, by which they are felted together.

The degree to which the felting of the separate layers is carried, before the assembling, or even the use of loose carded batt especially for the under layer, will depend upon the effect which is desired and upon the type of stock which is being used. For a figured felt e. g., as shown in Fig. 2, the hardening of the layers before assembly may be only one-half or two-thirds complete. The different layers may also be at different stages of hardening when they are assembled.

If it is desired to soften and blend the outlines of the pattern, the layer 10 will be softer when it is assembled than if a pattern with a sharp outline is desired. If a relatively smooth and level surface is desired in the finished felt, this may be achieved by using a softer or more slippery stock for either or both of the layers 10 and 11; and, as already stated the layer 10 will be relatively hard or soft depending upon the sharpness of the delineation desired of the figure.

These effects depend upon the type of stocks used as well as upon the degree of hardening. If, for example, a hard wool felt stock is being used, it will have less tendency to spread laterally during the final felting operation than would a more slippery stock like camel's hair, and accordingly, the preliminary hardening need not be carried so far as with the more slippery stock.

The fiber length or staple is also important in controlling this lateral spreading and especially for giving strength to the partially formed felt to hold the figure formed by perforation during the subsequent steps by which it is united with the under layers.

Because the combining of the layers is effected at a later stage than in the ordinary processes of felt manufacture it is desirable to choose the types of wools and raw materials that will give the bonding and combining of the materials. This, of course, becomes more important the harder is the felt of the assembled layers. Thus, the choice of materials is more important where sharp delineation and embossed effects are desired, than where softer felts can be combined.

With these additional considerations and limitations the stock chosen for the various layers in the felt of my present invention may be chosen upon considerations well known in the art.

In Fig. 4, I have shown an expanded lath pattern. This may be made in the same manner as already described in connection with Fig. 1, that is, by punching out from a sheet of partially formed felt the areas in which the under layer is to show through to the surface. This pattern, however, may be made with greater economy of stock by merely slitting the partially formed felt e. g., as shown in Fig. 5, and then stretching the stock so as to extend the slits into wider openings, as shown in Fig. 4. This pattern is representative of numerous patterns which can be made by slitting and stretching the stock without actually punching out any part of the stock. This method of forming the desired figures is, of course, included within the meaning of the terms "perforate" and "perforation", as used in this application.

In some cases it may be desirable to form more elaborate figures than are possible with the simple two color structures discussed in connection with Figs. 1 to 5. In Figs. 6 and 7, I have shown one method by which a three color pattern may be made. In this case, there are two perforated

layers 10 and 15. The perforations of the layer 10 are designed to expose a part of the layer 15 and in part to register with perforations of layer 15 to expose the layer 11. When these are united by the subsequent felting operation the 5 distinctive colors or textures of the three layers, 10, 15 and 11 will all appear at the surface, thus making possible a more complex figure than with the two layers as shown in the other figures.

As shown in Fig. 6, it is desirable where more 10 than one perforated layer is used to cut the face layer so that it overhangs slightly the edges of any under layer on lines where the intermediate perforated layer is not intended to show. Thus, as shown in Fig. 5, the subsequent felting operation may unite the face layer 10 directly with the under layer 11 over the undercut edge of the intermediate layer 15.

The number of colors and textures used in the surface decoration may be increased in other 20 ways. Thus, for example, the under layer 11 may be pieced together from strips of different stock or differently colored stock, e. g., as indicated by the broken lines 20 on Fig. 4, and these stocks may be combined during the initial felting operation before the assembling of the layers 10, 11, etc., or they may be pre-formed, as already described, and assembled at the same time as the layers 10, 11, etc., are assembled with one another. The figure of the face layer 10 in this 30 case is preferably designed so as to cover the border between the different pieces in the under layer 11, but in some cases such border may be taken advantage of as a part of the completed pattern.

The surface layer also may be pieced together from different kinds of or differently colored materials, and the perforations or openings through which the under layer or layers appear may be gaps left between adjacent pieces 40 instead of perforations cut in the pieces which comprise the surface layer.

In Fig. 8, I have shown another embodiment of my invention in which the figure appears solely as a contour effect with some difference in 45 texture due to the closer trimming of the surface fibers on the higher portions than on the depressed portion. In this case, the under layer 11a, instead of the face layer 10a, is perforated. As a consequence when the several layers are 50 combined, depressions are formed in the face layer 10a where the perforations occur in the under layer 11a. In this case, however, the figure is less sharply defined and in general, therefore, it will be found more desirable to perforate 55 the surface layer rather than the under layer.

Although in this specification and in the accompanying drawing I have shown and described in detail a preferred embodiment of my invention and various modifications thereof, it 60 should be understood that this is not intended to be exhaustive or limiting, but on the contrary, I have chosen these illustrations and described them with a view to explaining my invention in principle and the possibilities for modification 65 so that others skilled in the art may apply it in widely varying forms according to the particular conditions and requirements encountered.

What I claim is:

1. A figured felted fabric comprising a fibrous 70 face layer having openings therein and a fibrous under layer exposed at the face through said openings, said layers being integrally united by felting together of their fibers, the under layer being at least as heavy at said openings as be- 75

neath said face layer, and the face and under layers being trimmed to the same level throughout regardless of the figure.

5 2. A figured felted fabric as defined in claim 1 in which the weight of the under layer at the openings is less than equal to the combined layers at adjacent areas, and the face is trimmed to the same level throughout regardless of the figure, whereby the face of the under layer

where it is exposed in the openings is of looser texture than the adjacent face layer.

3. A figured felted fabric as defined in claim 1 in which the material of the under layer has spread laterally into the openings in the face layer, whereby the fabric exhibits a substantially level surface, and the under layer is heavier at said openings than under the face layer.

BELA FREYER.
